(57) **CLAIM**

The container for storing eyeglasses and other items, as shown and described.

DESCRIPTION

FIG. 1 is a perspective view of a container for eyeglasses and other items, showing my new design;

FIG. 2 is an exploded view thereof;

FIG. 3 is a front elevational view thereof;

FIG. 4 is a side elevational view thereof (with the opposite side being a mirror image thereof);

FIG. 5 is a rear elevational view thereof;

FIG. 6 is a top plan view thereof; and,

FIG. 7 is a bottom plan view thereof.

The broken line showing eyeglasses in FIG. 2 is for illustrative purposes only and forms no part of the claimed design.

1 Claim, 2 Drawing Sheets

FIG. 1**FIG. 2****FIG. 3****FIG. 4****FIG. 5****FIG. 6****FIG. 7**
